(57) CLAIM

The ornamental design for a golf tee holder, as shown and described.

DESCRIPTION

FIG. 1 is a perspective view of a golf tee holder, the broken line showing of a golf glove is for illustrative purposes only and forms no part of the claimed design;

FIG. 2 is a top plan view of the golf tee holder removed from the golf glove;

FIG. 3 is a side view of the golf tee holder removed from the golf glove; and,

FIG. 4 is an end view of the golf tee holder removed from the golf glove.

The broken line showing on the claimed design represents stitching.
